W. J. DUVALL

MATTRESS CLAMP

Filed March 27, 1925

INVENTOR.
Wm. J. DUVALL

BY Harry A. Beimes
ATTORNEY

UNITED STATES PATENT OFFICE.

WILLIAM J. DUVALL, OF ST. LOUIS, MISSOURI, ASSIGNOR TO SMITH & DAVIS MFG. CO., OF ST. LOUIS, MISSOURI, A CORPORATION OF MISSOURI.

MATTRESS CLAMP.

Application filed March 27, 1925. Serial No. 18,769.

My invention has relation to improvements in mattress clamps for folding beds, and consists in the novel features of construction more fully set forth in the specification and pointed out in the claim.

The present invention has for its object the provision of a clamp to hold down the foot end of the mattress when the bed is tilted or folded up, said clamp being simple in construction and easily operated. Briefly, the clamp consists in a lever pivoted to the foot end rail, the lever carrying a pawl which cooperates with a rack bar to hold the lever in operative position, the lever also carrying a mattress engaging finger for holding the mattress in place when the bed is eleaveted or folded up.

The advantages of the invention will be better apparent from a detailed description of the invention in connection with the accompanying drawings, in which—

Figure 1 is a side elevation of a tilting or folding bed showing the application of the clamp; Fig. 2 is an enlarged elevation of the bed end rail with parts broken away showing a pair of clamps in end elevation, one of which engages the mattress and the other being released; and Fig. 3 is a vertical cross-section taken on the line 3—3 of Fig. 2.

Referring to the drawings B represents a folding closet bed, the head frame 1 of which is hinged on the door frame F, and the bottom 2 is pivoted at 3 on the head frame. A detailed description of the bed itself is not attempted here because the bed is made the subject of a separate application under Serial Number 675,001, filed November 15, 1923.

Obviously, when the bed bottom is raised preliminary to swinging the bed into the closet the mattress M will fall toward the head frame 1 if it is not held down at the foot end. Therefore, a pair of clamps 5, 5 are provided, the same being mounted on the foot end rail 6 in spaced relation. Each clamp comprises a lever 7 pivotally mounted at 8 between the end rail 6 and a rack bar 9

secured to said end rail by rivets 10, 10, on which spacing washers 11 are disposed to hold the rack bar a fixed distance from the end rail. A mattress restraining member comprising a shank 12 having a laterally disposed finger 13 at its upper end is mounted on the lever 7 by straps 14, 14 in spaced relation. The shank 12 is free to turn in the straps 14 and has its lower end bent over, as at 15, to prevent it from slipping out of said straps.

The finger 13 extends over the mattress (Fig. 1) and may be securely held against the mattress by moving the lever to an inclined position (left side, Fig. 2) whereupon a pawl 16, pivotally mounted on the lever at 17, engages the teeth 18 of rack bar 9.

When the mattress is to be released the lever 7 is forced down a trifle to remove the pressure from the pawl 16 after which the pawl may be lifted from the teeth 18 and the lever raised as shown at the right of Fig. 2.

The finger 13 adjusts itself readily to mattresses of different thickness owing to the freedom of movement of the shank 12 in the straps 14. Owing to the inherent tension in the mattress when held down tightly by the clamps, it is practically impossible for the clamps to become accidentally loosened. Thus a clamp is provided, without springs or other tension devices, that tightly holds the mattress in place on the bed bottom.

Having described my invention, I claim:—

A mattress clamp for holding the mattress on a bed, said clamp comprising a lever arm pivotally mounted on a bed end rail, a mattress restraining member consisting of a shank secured to and longitudinally adjustable on said lever arm, said shank having a laterally disposed finger for engaging the mattress, a pawl pivotally mounted on said lever arm, and a rack-bar secured to said end rail for co-operating with the pawl to hold the lever arm in depressed position.

In testimony whereof I hereunto affix my signature.

WILLIAM J. DUVALL.
